(57) **CLAIM**

We claim the ornamental design for a hair styling and hair care apparatus, as shown and described.

DESCRIPTION

FIG. 1 is a top perspective view of a hair styling and hair care apparatus showing our new design;

FIG. 2 is a bottom perspective view thereof;

FIG. 3 is a side view thereof;

FIG. 4 is a top view thereof;

FIG. 5 is a bottom view thereof;

FIG. 6 is a front view thereof; and,

FIG. 7 is a rear view thereof.

The view opposite the side view of FIG. 3 is a mirror image thereof, and therefore, is omitted.

The broken lines in the drawings depict portions of the hair styling and hair care apparatus that form no part of the claimed design.
